UNITED STATES PATENT OFFICE.

CATHERINE FRASER PITMAN, OF STOCKTON, CALIFORNIA.

DESIGN FOR A BAG OR SIMILAR ARTICLE.

Application filed October 7, 1925. Serial No. 15,051. Term of patent 3½ years.

To all whom it may concern:

Be it known that I, CATHERINE FRASER PITMAN, a citizen of the United States, residing at Stockton, San Joaquin County, State of California, have invented a new, original, and ornamental Design for a Bag or Similar Article, of which the following is a specification, reference being had to the accompanying drawings, forming part thereof.

Fig. 1 is a front view showing my new design;

Fig. 2 is a rear view of the same.

I claim:

The ornamental design for a bag or similar article, substantially as shown.

CATHERINE FRASER PITMAN.
